UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,234, dated April 3, 1888.

Application filed January 26, 1888. Serial No. 262,079. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists, principally, of the large 20 group or cluster A of leaf and flower forms, surrounded by other and smaller groups or clusters of leaf and flower forms, the whole disposed as shown over the surface of the carpet upon a suitable ground.

The figure A consists of two large central

flower forms, one appearing partly in profile. Underlying these flower forms, at the under side of the figure, are large leaf forms having 25 deep serrations. At the upper part of the figure, underlying the large flower forms, are a number of small leaf forms with deep serrations, partly overlying one another. From various parts of the border of this figure extend or project small twigs or branches, some of which bear small leaves. Surrounding this principal group or cluster are several smaller clusters of similar leaf and flower forms, from under which also project small twigs or 35 branches.

What I claim as new, and desire to secure by Letters Patent, is--

The design for carpets, consisting of the design substantially as shown.

JAS. L. FOLSOM.
